G. P. S. CROSS

DIVIDED LAST

Filed May 2, 1921

UNITED STATES PATENT OFFICE.

GARRETT P. S. CROSS, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

DIVIDED LAST.

Application filed May 2, 1921. Serial No. 465,951.

This invention relates to divided lasts for making boots and shoes, and is illustrated as embodied in a separable last, or one the heel part of which can be entirely separated 5 from the forepart, preferably while the latter remains undisturbed in a shoe, to permit heelng on a jack, for example.

One of the marked achievements in securing the requisite simplicity, cheapness 10 and reliability necessary in such a last was provided by the last invented by William C. Stewart and described and claimed in United States Letters Patent No. 1,432,217, granted Oct. 17, 1922, on his application. It is a 15 principal object of the present invention still further to improve divided lasts of the type disclosed in said Letters Patent, while retaining the advantages thereof.

Accordingly, an important feature of the 20 invention resides in a heel part, a forepart and a novel bonding means operable for collapsing the last, and preferably for actually separating the last parts as an incident of shoemaking, by virtue of a relative lateral 25 or twisting movement of the last parts. To this end the illustrated bonding means comprises a hook and is preferably provided with two oppositely facing hooks, one in each last part, facing substantially parallel 30 to the last periphery in that neighborhood, and separable by a twisting movement of small angular extent. Advantageously such a bonding means is located near the periphery of the last in order that a minimum 35 twist may effect the requisite movement in the bonding means.

In accordance with another important feature of the invention, the bonding means is carried entirely in the upper part of the 40 last, and preferably has associated with it means normally preventing operation of the bonding means to collapse the last. This location of the bonding means, as will be pointed out, effects a maximum of strength 45 and convenience with a minimum of bonding structure. The second-mentioned means, in accordance with another feature of the invention, may be rendered inoperative by a relative and preferably separational movement of the last parts at the bottom of the last, which will be permitted by the normal looseness of the parts when bonded only at the top.

These and other features of the invention comprising certain combinations and arrangements of parts will be understood from the following description of a preferred embodiment thereof selected for purposes of illustration and shown in the accompanying drawings in which,

Fig. 1 illustrates the last just after the disengagement of the last parts;

Fig. 2 is a view of the bonding and its co-operating means, looking from front to rear, the main portion of the forepart being removed;

Fig. 3 shows the forepart and shoe after separation from the heel part;

Fig. 4 shows the heel part.

Fig. 5 is a section of the bonding means 70 on the line 5—5 of Fig. 2.

Fig. 6 illustrates the angle of cut.

The illustrated last is divided by a substantially plane cut extending preferably upward and forward, and such that the last 75 will lengthen somewhat as the parts are slid over each other into operative position along that plane. The secant faces are advantageously covered with metallic plates to secure strength and ease of operation, and to 80 serve as templets, if desired, in the finishing of the last parts.

The heel part 10 is faced with the plate 12, fastened by suitable screws 14. The 85 illustrated plate is provided with a round boss or pin 16 and another boss 18, shown as of oblong shape. The boss 18 is located near the bottom of the last, the boss 16 being farther toward the center. The upper part of the heel part is provided with a bonding member 20 formed as a laterally extending hook. This hook is anchored firmly in the heel part by any convenient but strong means such as a flanged screw 22, and is preferably provided with a shoulder to hold the plate 12 firmly to the heel part. A spot or depression 25 is shown at the upper tip of the secant face.

The forepart 24 is provided with a similar plate 26 fastened on with suitable screws 28. The plate is provided with a hole 30 registering with and fitting the boss 18, and a key hole shaped aperture 32, the lower small end of which registers with and fits the boss 16 when the parts are in operative 105 position, as shown in Fig. 2. The wood of

the forepart is shown hollowed out beneath this portion of the aperture 32, as shown at 34, to give the boss 16 free entry.

The upper part of the secant face of the forepart carries a hook 36 inserted in a hole 38 (see Fig. 5). This hook registers with and engages the hook 20 when the last parts are in operative position, and is provided with a flange 40 which anchors the plate 26 and a shoulder 42 engaged by a screw 44 to anchor the hook. The hook 36 occupies only one side of the hole 38, the hook 20 having ample clearance to enter and engage the hook 36. A spring pressed plunger 46 in a hole 48 in the plate 26 registers with the spot 25.

As shown in Fig. 6, the cut is preferably not perpendicular to a vertical longitudinal plane in the last, but is canted considerably to one side so as to be perpendicular to the instep ridge. This structure enables the screw 44 to be driven perpendicular to the plate 26 straight into the center of the instep ridge to any distance requisite for strength.

The only bonding means between the last parts is the two hooks in the cone, which are amply strong to hold the last parts in position when inverted on a jack supporting it at its ends, in which position it receives the severest machine shoemaking stresses, which are therefore only such as to place the bottom of the last in compression. The last parts are disengaged by a relative rotation or twist about the pivot 16 in the end of the hole 32. This twisting movement is normally prevented by the interfitting boss 18 and hole 30, the plunger 46 holding the lower parts of the plates in contact and accordingly the boss and hole in engagement, when no shoe is on the last. The plunger 46 and recess 25 also cooperate to prevent twisting and separation of the last parts in case the boss 18 accidentally comes out of the hole 30, as might occur if the last were dropped when it had no shoe on it. There is enough looseness in the connection, however, to permit the boss 18 and hole 30 to be disengaged by the application of a bending stress in a vertical plane. When the last is in the shoe, the tension of the upper, which may have been previously formed, normally keeps the bottom of the joint between the last parts tightly closed. When the last and shoe are inverted and placed on a jack pin (see Fig. 1), the bending stress mentioned is easily applied by pressing down on the toe. This releases the boss 18, the thickness of which need not be over 0.030 or 0.040 inch, and pushes in the plunger 46, bringing the upper edges of the plates 12 and 26 together. The operator can then, without releasing his grip on the shoe, twist the forepart around the pivot 16 until the hooks 20 and 36 disengage. This position is shown

in Fig. 2, in which the wooden part of the forepart has been removed leaving only the plate 26.

The parts being in this position, an upward pull by the operator removes the hook 20 from the hole 38 completely, and the forepart and shoe can be stripped upward away from the heel part, the boss 16 finding clearance in the broader part of the hole 32, which, in the reverse operation of inserting the heel part, serves as a guide for the boss 16 to locate it properly at the small end of the hole 32. The forepart of the last is not disturbed in the shoe by the removal. There is a considerable advantage in this type of relative movement between the shoe and the heel part, since the lower and widest portion of the heel part passes through the shoe by a forward and upward or a backward and downward movement, and thus does not have to force its way through the upper rear counter portion of the shoe, where the counter is narrowest and stiffest. The heel part may be replaced by a reverse operation, as suggested. This reverse operation, owing to the shape of the cut between the last parts, will effect stretching action on the upper due to the fact that the last extends in length somewhat as its parts move into operative position.

The boss 18 is preferably designed strong enough to carry not only any twisting stress but any shearing stress occurring in the shoemaking, tending to slide one last part on the other. The hooks or other similarly situated bonding members therefore have only to carry the tension due to the action of the last as a beam, and accordingly run a minimum risk of becoming cramped or jammed.

The boss 16 is not indispensable. The boss 18 and its closely fitting hole 30 are entirely capable of holding the last firmly against the twisting movement which prepares it for collapse. The boss or pin 16 is a convenience in effecting the twisting and unhooking movement, providing a definite pivot removed from the hooks, so that the operator merely has to twist the parts relatively and the hooks must disengage. The last could, however, be worked without it, somewhat less conveniently.

The secant face on one of the last parts is a smooth metal surface except for the projection 46, which is not unyielding. This feature greatly facilitates the movement of the forepart and heel part over each other as there is nothing which can catch and lock on the projections of the other last part except the holes into which the projections are intended to fall operatively. The element 46 has here been placed in the forepart because of the scantiness of material in the locality marked 10 in Fig. 1.

The location of the bonding means near

the periphery secures the maximum looseness at the opposite part of the cut between the last parts for a given closeness of fit between them. This looseness is here utilized as a 5 characteristic of a locking means. The peripheral location of the bonding means also secures the maximum relative movement of the bonding elements for a given relative disturbance of the heel part and the forepart, and the formation of the bonding members integral with the last parts makes them relatively disengageable by a mere relative movement of the last parts, the operator 10 not being obliged to grope after and to adjust just movable parts. Further, the location of the bonding means in the upper part of the last places it just where it is needed to take the bending stresses impressed on the last by machine shoe-making most economically 15 with bonding members of minimum size; where the looseness in a lasted or formed upper as compared with conditions nearer the bottom can be utilized to effect easily relative movement of the bonding members when 20 desired; and where any accidental failure to operate is most easily ascertained through the open top of the shoe and remedied.

A valuable feature of the invention consists in the relative locations of the bosses 18 and 16, in connection with the direction of relative twist required to operate the bonding mechanism. The boss 16 is near one end of the boss 18, and the direction of twist is such as relatively to displace the boss 18 and 25 its slot 30 in the same direction as they tend to move during the heel part removing or replacing movement. Fig. 2 illustrates this point. In this figure the twist has been performed and the end of the slot 30 has moved relatively upward (in the figure) over the boss 18. The upward movement of the forepart and plate 26 will carry this movement still further. The placing of the boss 16 at one end of the boss 18 causes the initial overlap 30 to come definitely at the right or far ends of 18 and 30, the near ends sliding relatively longitudinally of the slot and boss 18. If the twist were in the other direction, the far ends of 18 and 30 would be relatively 35 displaced oppositely and the upward movement of the plate 26 would carry the far ends of the boss and slot back over one another, where they would tend to catch, and impede the heel part removing operation. The same 40 advantage is found in the reverse operation.

The "twist lock" or rotary shearing movement used in operating the last parts has a distinct advantage in that the relative movement of the last parts does not require so 45 great a relative displacement of the last parts and the stiff parts of the shoe as do the movements of a last which collapses about a horizontal hinge or whose bonding mechanism has to be "thrown" by an initial relative sliding movement of the last parts.

Further, the relative twisting movement is one which is unlikely to be impressed on the last by accident.

Having described my invention, what I claim as new and desire to secure by Letters 70 Patent of the United States is:—

1. A divided last having a heel part and forepart, the former of which is removable in collapse leaving the latter in the shoe, and bonding mechanism normally holding 75 them in extended position, constructed and arranged to release said parts for collapsing movement upon a relative twisting movement of said forepart and heel part.

2. A separable last having a heel part and forepart constructed to permit relative movement for collapsing the last, and means for holding said parts together, constructed and arranged to be rendered inoperative by a relative twisting movement of said forepart 85 and heel part about a longitudinal axis.

3. A divided last having a heel part and forepart constructed to permit relative movement for collapsing the last, and means for holding said parts together, constructed 90 and arranged to be disengaged by a rotary shearing movement of said forepart and heel part about a longitudinal axis.

4. A last having a heel part and a forepart and a bonding means joining them constructed and arranged to permit the heel part and forepart to be separated as an incident of shoemaking, said means comprising 95 a hook directed toward the side of the last and integrally mounted on one of said last parts.

5. A last having a heel part and a forepart separated on a cut running completely through the last, and a bonding means joining them constructed and arranged to permit the heel part and forepart to be separated as an incident of shoemaking, said means comprising 105 a horizontally directed hook.

6. A last having a heel part and a forepart and a bonding means joining them constructed and arranged to permit the heel part and forepart to be separated as an incident of shoemaking, said means comprising a hook integrally mounted on one of said last parts 110 and facing substantially parallel to the last periphery in the neighborhood of the hook.

7. A last having a heel part and a forepart and a bonding means joining them constructed and arranged to permit the heel part and forepart to be separated as an incident of shoemaking, said means comprising 115 a hook near the periphery of the last and facing substantially parallel to the last periphery in the neighborhood of the hook.

8. A last having a heel part and a forepart and a bonding means joining them constructed and arranged to permit the heel part and forepart to be separated as an incident of shoemaking, said means being located 120 at least substantially one half of the 125 last.

distance from the main longitudinal axis of the last to its periphery and being operable to permit collapse of the last by a twisting movement about a longitudinal axis of the last.

5 9. A last having a heel part, a forepart, and a pair of hooks located one on each last part at least substantially one half of the distance from the main longitudinal axis of the last to its periphery and operable to permit collapse of the last by a relative twisting movement of the last parts about a longitudinal axis.

10 10. A divided last having a heel part and forepart and a separable bonding mechanism comprising a pair of oppositely directed hooks, one integrally mounted on each last part, said hooks being directed toward the sides of the last, respectively.

15 11. A divided last having a forepart and heel part and bonding devices for holding them in extended position in a shoe, said devices being constructed to release said last parts for collapsing movement by a relative twisting movement of the said parts about a longitudinal axis, and positively acting means for normally preventing said relative twisting movement.

20 12. A divided last having a forepart and heel part and bonding devices for holding them in extended position in a shoe, said devices being constructed to release said last parts for collapsing movement by a relative twisting movement of the said parts, and rigid interfitting means on said last parts for normally preventing said relative twisting movement.

25 13. A divided last having a forepart and heel part and bonding devices integrally mounted upon them for holding them in extended position in a shoe, said devices being constructed to release said last parts for collapsing movement by a relative twisting movement of the said parts about a longitudinal axis, and interfitting means on said last parts for normally preventing said relative twisting movement, said interfitting means being disengageable by a relative movement of said forepart and heel part

30 about a transverse axis.

40 14. A divided last having a forepart and heel part and bonding devices for holding them in extended position in a shoe, said devices being constructed to release said last parts for collapsing movement by a rotary shearing movement of the said parts, and interfitting means on said last parts for normally preventing said relative twisting movement, said interfitting means being disengageable by virtue of the ordinary looseness of the parts.

45 15. A divided last having a forepart and heel part and bonding devices for holding them in extended position in a shoe, said devices being constructed to release said last

50 parts for collapsing movement by a relative twisting movement of the said parts about a longitudinal axis, a pivot for guiding said movement, interfitting means on said last parts for normally preventing said relative twisting movement, said interfitting means being disengageable by a relative movement of said forepart and heel part about a transverse axis, and a member for normally impeding said last described relative movement.

55 16. A divided last having a forepart and heel part and bonding devices for holding them in extended position in a shoe, said devices being constructed to release said last parts for collapsing movement by a relative twisting movement of the said parts, interfitting means on said last parts for normally preventing said relative twisting movement, said interfitting means being disengageable by a relative movement of said forepart and heel part about a transverse axis, and a resilient mechanism for normally preventing said last described relative movement.

60 17. A separable last comprising a forepart, a heel part and bonding means for holding said parts in extended position in a shoe, constructed and arranged to release said parts for relative movement, and separable by a relative lateral movement of the localities containing the bonding means.

65 18. A divided last comprising a forepart and a heel part, a bonding mechanism located wholly in the cone of the last to hold the last in extended position in the shoe, said mechanism comprising a laterally directed hook on one last part arranged to engage the other and to disengage it upon a lateral movement of one last part relatively to the other, and one of said last parts having a boss and the other having a depression arranged to interengage to prevent said lateral movement.

70 19. A divided last comprising a forepart and a heel part, a bonding mechanism located in the cone of the last to hold the last in extended position in the shoe, said mechanism comprising a laterally directed hook on one last part arranged to engage the other, and to disengage it upon a lateral movement of one last part relatively to the other, the last comprising also a pivot for guiding said lateral movement, and a boss on one last part and a depression in the other arranged to interengage to prevent said lateral movement, said boss and depression being located below the longitudinal axis of the last so that they are held in engagement by the lasting tension of the shoe.

75 20. A divided last comprising a forepart and a heel part, a bonding mechanism located in the cone of the last to hold the last in extended position in the shoe, said mechanism comprising a laterally directed hook on one last part arranged to engage the other

and to disengage it upon a lateral movement of one last part relatively to the other, and one of said last parts having a boss and the other having a depression arranged to interengage to prevent said lateral movement, said boss and depression being located below the longitudinal axis of the last so that they are held in engagement by the lasting tension of the shoe, there being sufficient looseness of the parts to permit disengagement of said boss and depression against the shoe tension, to permit the said relative lateral movement of the last parts.

21. A separable last comprising a forepart, a heel part and a bonding means consisting of a laterally facing hook on one last part and a co-operating member on the forepart, the hook and member being disengageable by a relative twisting movement of the last parts; whereupon the heel part may be moved relatively upwardly over the forepart to remove it from the shoe without disturbance of the forepart.

22. A separable last having a heel part and a forepart divided by a substantially plane transverse cut and a bonding mechanism for holding them in extended position constructed and arranged to permit separation and connection of said parts upon a relative twisting movement about an axis perpendicular to the plane of the cut.

23. A divided last having a transverse substantially plane cut between the heel part and forepart, a longitudinal pivot extending from one of said parts into the other, and a bonding mechanism for connecting said last parts constructed and arranged to come into engagement or disengagement by a relative rotation of the last parts about the pivot.

24. A divided last having its bonding means located solely in the cone thereof, and means on the heel part and forepart constructed and arranged normally to prevent movement of the bonding means to permit collapse of the last.

25. A divided last having its bonding means located in the cone thereof, and means located between the longitudinal axis of the last and its bottom on the heel part and forepart constructed and arranged normally to prevent operating the bonding means to permit collapse of the last.

26. A divided last having its bonding means located in the cone thereof, and means located below the longitudinal axis of the last on the heel part and forepart constructed and arranged to prevent operation of the bonding means to permit collapse of the last, said lower means being rendered inoperative by a slight movement of separation between the lower portions of the last parts, whereby the bonding mechanism is rendered operable to permit collapse of the last.

27. A divided last having its bonding means integrally located on the last parts 65 and in the cone thereof, and interengaging means located below the longitudinal axis of the last on the heel part and forepart constructed and arranged to prevent operation of the bonding means to permit collapse 70 of the last, said interengaging means being separable by virtue of the ordinary looseness of the parts whereby the bonding mechanism is rendered operable to permit collapse of the last.

28. A divided last comprising a heel part and a forepart separated by a cut extending generally transverse to the last, that part of the cut at the top of the cone being substantially out of perpendicular to a vertical 80 longitudinal median plane of the last in order to bring it into substantial perpendicularity to the instep ridge.

29. A separable last comprising a heel part and a forepart with their secant faces 85 in contact, one of said parts having its secant face free from unyielding projections of any kind, a hook projecting from the upper portion of the secant face of the other last part, and the first-named last part having an aperture in its secant face into which the said hook projects, and also having an engaging face in the aperture below the surface of its secant face arranged to engage the hook to hold the last parts together.

30. A separable last having a bonding means operable by a relative rotation of the last parts, a rib on one part and a cooperating slot on the other for locking the bonding means, and a pivot means at one end of the rib and slot structure about which to effect relative displacement of the rib and slot to cause engagement or disengagement of the bonding means, the last parts being constructed for junction or separation by 100 a further relative movement in the same direction.

31. A separable last having a bonding means and a rib and slot structure for holding said bonding means in operative position, said bonding means being disengageable by a relative movement of the rib and slot over each other, and the last parts being then separable by a continued movement in the same direction.

32. A separable last having a bonding means and a rib and slot structure for holding said bonding means in operative position, said bonding means being engageable by a relative movement of the rib and slot 120 over each other, and the last parts being initially relatively approachable by a relative movement in the same direction.

In testimony whereof I have signed my name to this specification.

GARRETT P. S. CROSS.
